DRAIN RELIEF DEVICE

Joseph F. Kestleot, Chicago, Ill.

Application December 8, 1942, Serial No. 463,256

5 Claims. (Cl. 182—1)

My invention relates to the drain systems in homes, factories and other buildings, and more particularly to apparatus for anticipating or dealing with tendencies of water in drain systems to rise and flood basement or living quarters, and my main object is to provide a device which will relieve the rise or backing up of water from drains and lead excess water out to a distant point for discharge.

A further object of the invention is to provide a device of the above character which is applicable to a common building utility in which water from the drain system is most likely to rise and where a compact and convenient means may be applied to receive such water.

Another object of the invention is to provide a device which may be easily and quickly fitted to a toilet bowl to receive water that may back up or rise into the same.

A still further object of the invention is to provide means to facilitate the universal fit of the device and the stability thereof when completed.

With the above objects in view, and any others which may suggest themselves from the description to follow, a better understanding of the invention may be had by reference to the accompanying drawing, in which—

Figure 1 is a longitudinal section of a typical toilet bowl installation showing the main part of the relief device applied thereto;

Figure 2 is a plan view;

Figure 3 is an enlarged section on the line 3—3 of Figure 2; and

Figure 4 is a partial section of a basement drain system, showing the application of the relief device and containing enlarged portions within dot-and-dash lines.

In basement drain systems designed along conventional lines it is inevitable that drain water should back up and flood the basement to a greater or less extent in the event of a storm or heavy downpour. Drain stoppers have been devised for the purpose of shutting off the drain outlets but in some cases the water pressure becomes so great under the basement floor that it causes the same to bulge and even crack in an effort to find avenues of escape. Thus, while drain stoppers may function efficiently during light rains, they are a menace to a floor structure when heavier rains occur, often causing considerable damage. In view of this situation it has been my intention not to stop the backing up or rise of the drain water, but rather to afford relief

thereto and lead the excess to a point of discharge outside of the building.

In accordance with the foregoing, 10 shows a basement floor and 11 a typical toilet bowl installation. While the bowl outlet is not at the lowest point where excess water can be taken up for the purpose of discharge, it is a better utility than a bath tub or other lower vessel because the zone in which the take-up is applied is small or compact.

The outlet of the bowl 11 is indicated at 12, and this outlet is employed as a feed for the back water into a vertical pipe 13 applied over the outlet.

15 A seal between the pipe 13 and the outlet 12 is provided in the form of a soft rubber cup 14 which is of a size and curvature to readily adapt itself to the mouth or entrance of the outlet 12, whether such mouth or entrance is circular, oval or of any other irregular form in different makes of toilet bowls.

20 Since the cup 14 may assume an irregular form to procure a proper fit, I employ a backing element of firmer construction to maintain the cup 14 in proper contact. The element referred to is in the form of a smaller, inverted cup 15 of stiffer rubber than the cup 14.

25 The cups 14 and 15 are assembled on the pipe 13 by threading the same and mounting a series of securing devices thereon. Thus, the first device is a nut 16. Next comes a ring 17. The bottom of the cup 15 has a center opening 18, permitting the cup to be slid on the pipe 13 to seat against the ring 17. Next comes a ring 19 which is slid up against the inner side of the cup 15. The cup 14 has a center opening 20 enabling it to be mounted over the pipe 13 to seat against the ring 19. A final nut 21 completes the assembly. It is evident that the parts are applied to the pipe in the order mentioned, and that the nuts 16 and 21 serve to clamp the cups 14 and 15 in place.

30 While the assembly of the pipe 13 is fitted as shown, it requires fastening means in order to hold this position. Such fastening means primarily involve a cross plate 22 perforated at 22a and slidable along the pipe 13 to be stationed at any suitable point along the same by means of a supporting nut 23 on the under side. The plate 22 is made with tubular formations 24 on opposite sides, such formations being adapted to receive horizontal rod arches 25 in the ends, the legs of the arches being slidable in the tubular formations. The end portions 26 of the arches 25 35 are slightly curved in an outward direction and

divergent; and they preferably carry wrappings 27 of rubber or other soft material.

Figure 3 shows that the cross plate 22 has been raised to a height suitable for the extension of the arches 25 to meet or lie close to the walls of the bowl. The rim 28 of the latter overlies the outer end portions of the arches. Now, the rotation of the nut 23 in a rising direction will have the effect of depressing the assembly of the pipe 13 until the cup 14 makes a complete or tight fit with the mouth or entrance of the bowl outlet 12, the assembly of the plate 22 now serving as a clamp to maintain the fit of the cup.

It may now be assumed that back water from the drain system will not rise into the bowl but only in the pipe 13. An elbow 29 is applied to the upper end of the latter to lead into a horizontal pipe 30. Figure 4 shows that this pipe is led through a wall 31 to a point outside of the building for the discharge of the back water.

It is evident that the relief afforded by the pipes 13 and 30 will keep the immediate zone of the basement floor from receiving any back water. However, in case any drain outlets occur in other parts of the basement through which water may rise despite the application of the relief device, Figure 4 shows that a branch 30a may be directed from the pipe 30 to each outlet, the lower end of the branch being threaded and screwed into the outlet receptacle 32.

The application of the improved drain relief is a comparatively simple task for the janitor or caretaker of a building in which it is to be used. Thus, the apparatus is kept in a handy closet or corner, and when the indications are that a storm may bring down a heavy rain or downpour it is a simple matter to apply the main or initial assembly of the drain relief to the toilet bowl as described. In case the arrangement in the basement does not permit the convenient connection of the discharge pipe 30 or the leading thereof over the zones of the drain outlet 32, some lengths of garden hose may be kept handy to join the pipe in suitable sections. The branches 30a may be short, as the general course of the discharge pipe 30 is only a little more than a foot above the floor. The pressure of the back water will insure its discharge in case the pipe 30 is led directly out of the basement over lower ground, or most of the discharge in case the pipe must emerge at an elevation, as shown in the right hand portion of Figure 4.

It will be evident from the above description that the novel drain relief device is basically a piece of equipment which can be applied to make a readily adaptable fit with the outlet opening of any toilet bowl, while including resilient means to maintain the form of the fit as well as positive means to hold the device firmly in the bowl. Further, the arches 25 are adjustable toward or from each other to fit bowls of different widths, while the divergent form of the arch ends 26 enables the arches to fit at points back or forward of the bowl center, according to the location of the bowl outlet 12, so that the position of the pipe 13 may be vertical or as nearly so as conditions will permit. Finally, it is apparent that the device is made up of parts which are few, simple and possible of being easily applied or adjusted by any mechanically inclined person.

While I have described the drain relief device along specific lines, various minor changes or refinements may be made therein without departing from its principle, and I desire to consider all

such changes and refinements as coming within the scope and spirit of the appended claims.

I claim:

1. In combination with a drain duct in a basement floor or the like which is underlaid by water and subject to overflow, a removable drain relief device consisting of an eduction pipe opening into and leading upwardly from said duct, sealing means for sealing said pipe around said duct to prevent direct escape of water therefrom, and a discharge pipe connected with said eduction pipe and having its discharge end located in a position subjected to less pressure than that to which the water to be drained is subjected.

5 2. In combination with a drain duct in a basement floor or the like which is underlaid by water and subject to overflow, a removable drain relief device consisting of an eduction pipe opening into and leading upwardly from said duct, sealing 10 means for sealing said pipe around said duct to prevent direct escape of water therefrom, a discharge pipe connected with said eduction pipe and having its discharge end located in a position subjected to less pressure than that to which the 15 water to be drained is subjected, and means for holding said eduction pipe in fixed relation to said drain duct, said sealing means comprising a compressible sealing cup carried by the eduction pipe, and backing means adjustable on said 20 eduction pipe and adapted to exert pressure against said cup to seal the same against said drain opening.

25 3. In combination with a drain duct in a basement floor or the like which is underlaid by water and subject to overflow, a removable drain relief device consisting of an eduction pipe opening into and leading upwardly from said duct, sealing means for sealing said pipe around said 30 duct to prevent direct escape of water therefrom, a discharge pipe connected with said eduction pipe and having its discharge end located in a position subjected to less pressure than that to which the water to be drained is subjected, detachable means for holding said eduction pipe in fixed relation to said drain duct, said sealing means comprising a compressible sealing cup carried by the eduction pipe, and backing means adjustable on said 35 eduction pipe and adapted to exert pressure against said cup to seal the same against said drain opening.

40 4. In combination with a drain duct in a basement floor or the like which is underlaid by water and subject to overflow, a removable drain relief device consisting of an eduction pipe opening into and leading upwardly from said duct, sealing means for sealing said pipe around said 45 duct to prevent direct escape of water therefrom, and a discharge pipe connected with said eduction pipe and having its discharge end located in a position subjected to less pressure than that to which the water to be drained is subjected, detachable means for holding said eduction pipe in fixed relation to said drain duct, comprising a plate adjustable upon said eduction pipe, horizontal rods slidable outwardly from said plate and adapted to engage a fixed fitting adjacent the drain duct and said sealing member comprising a compressible sealing cup carried by the eduction pipe and backing means adjustable on 50 said eduction pipe and adapted to exert pressure against said drain opening, said backing means including an inverted cup slidable on said eduction pipe and a member screw threaded onto said eduction pipe and adapted to bear against said inverted cup.

55 5. In combination with a drain duct in a basement floor or the like which is underlaid by water and subject to overflow, a removable drain relief device consisting of an eduction pipe opening into and leading upwardly from said duct, sealing means for sealing said pipe around said 60 duct to prevent direct escape of water therefrom, and a discharge pipe connected with said eduction pipe and having its discharge end located in a position subjected to less pressure than that to which the water to be drained is subjected, detachable means for holding said eduction pipe in fixed relation to said drain duct comprising a plate adjustable upon said eduction pipe, horizontal rods slidable outwardly from said plate and adapted to engage a fixed fitting adjacent the drain duct and said sealing member comprising a compressible sealing cup carried by the eduction pipe and backing means adjustable on 65 said eduction pipe and adapted to exert pressure against said drain opening, said backing means including an inverted cup slidable on said eduction pipe and a member screw threaded onto said eduction pipe and adapted to bear against said inverted cup.

sure against said cup to seal the same against said drain opening.

5. In combination with a drain duct in a basement floor or the like which is underlaid by water and subject to overflow, a removable drain relief device consisting of an eduction pipe opening into and leading upwardly from said duct, sealing means for sealing said pipe around said duct to prevent direct escape of water therefrom, and a discharge pipe connected with said eduction pipe and having its discharge end located in a position subjected to less pressure than that to which the water to be drained is subjected, detachable means for holding said eduction pipe

in fixed relation to said drain duct comprising a plate adjustable upon said eduction pipe, horizontal rods slidable outwardly from said plate and adapted to engage a fixed fitting adjacent the drain duct and said sealing member comprising a compressible sealing cup carried by the eduction pipe and backing means adjustable on said eduction pipe and adapted to exert pressure against said cup to seal the same against said drain opening, said backing means including an inverted cup slidable on said eduction pipe, and a member screw threaded onto said eduction pipe and adapted to bear against said inverted cup.
